SUSTAINING ROTOR FOR ROTATING WING
AIRCRAFT

Harold T. Avery, Oakland, Calif.

Application February 17, 1947, Serial No. 729,071

5 Claims. (Cl. 170—160.5)

1

This invention relates to rotating wing aircraft and particularly to improvements in the sustaining rotors for such craft. As is well known, such rotors may be of either the articulated or the non-articulated type. In rotors of the non-articulated type each blade of the rotor is constructed in fixed relationship to the rotor hub except for freedom of the blade to be rocked on its own longitudinal axis to effect change in blade pitch, and for such further changes in relationship as may be introduced by the bending of the blades due to their own flexibility. In rotors of the articulated type, the blades ordinarily retain the same freedoms of movement relative to the hub as in rotors of the non-articulated type plus: (1) the freedom provided by introducing a so called "flapping" hinge at the root of each blade (or in some cases such a hinge common to more than one blade) permitting the blade to be rocked up and down in response to the forces acting on it in flight, and usually also, (2) the freedom provided by additionally introducing near the root of each blade a so called "drag" hinge permitting it to be angularly displaced in its general plane or cone of rotation.

All such rotors, and more particularly rotors of the articulated type, are more or less subject to undesirable amounts of vibration. Such vibrations are largely due to the manner in which the center of gravity of such rotors is continually shifting, so that a rotor which is perfectly balanced under one set of conditions will be out of balance under other conditions. These shifts are primarily due to unequal displacement of the respective blades about their respective drag hinges, and/or unequal rocking of the blades about their respective flapping hinges, and/or (particularly in the case of non-articulated rotors) unequal flexing of the blades.

One of the most troublesome sources of such unequal displacement and rocking is to be found in aerodynamic dissimilarity between the respective blades. Very slight amounts of twist or warp, or imperfection in part of the airfoil surface will very readily cause one blade to produce more or less lift than the other blades do under the same circumstances, and hence cause that blade to continuously ride higher or lower than the track described by the other blades in their circuits. So long as all blades follow exactly the same track, and particularly if there are more than two blades in the rotor, inequalities in the flapping angles of the blades at different points in the circuit do not tend to cause very serious vibration, for under these circumstances the center of gravity remains

permanently displaced in a direction generally opposite to that part of the circuit in which the blades rock the highest and the center of gravity remains very nearly fixed relative to the craft. 5 However, if the aerodynamic characteristics of one blade cause it to permanently track any higher or lower than the others, it will cause the center of gravity of the rotor to be shifted away from or toward that blade in all parts of its circuit, thus producing substantially the same effect as an eccentrically located weight rotating with the rotor, which, of course produces bad vibration. Also, if the pitch setting of a blade with such different aerodynamic shape is readjusted relative 10 to that of the other blades by an amount sufficient to bring it back into substantially the track described by the other blades, its difference in aerodynamic shape is very apt to cause a difference in drag which will cause that blade to be 15 displaced differently from the others about its drag hinge, thus causing a shift in the center of gravity of the rotor in the direction of such difference of displacement, which again is equivalent to an eccentric weight rotating with the rotor and 20 causes bad vibration. A great deal of the trouble and expense involved in the manufacture and maintenance of articulated rotors is due to the effort to secure and maintain perfect aerodynamic similarity, as well as perfect mass balance, 25 between all blades.

As long as a rotor is sustaining a craft the lift exerted along the blades cause them to cone upwardly, or in the case of a non-articulated rotor at least flex upwardly, so that the centers of 30 mass of the blades normally describe circles about the rotor axis offset vertically above the plane of the blade hinges or blade roots. It is usual in rotating wing craft to exert control of the craft in the various horizontal directions by imposing, 35 cyclic changes of pitch upon the blades, thus causing them to travel higher in certain parts of their circuits than others, thereby tilting the cone described by the rotor blades about the blade hinges, or the equivalent points of flexure in a 40 non-articulated rotor, and causing the centers of mass of the blades to describe a circle which under these circumstances will be eccentrically located relative to the rotor axis. The moment of inertia of each blade about the rotor axis will 45 then cyclically increase and decrease causing cyclic changes in the angular momentum and therefore vibration unless each blade is permitted to be freely displaced on its drag hinge so as to angularly accelerate and decelerate sufficiently to 50 maintain constancy of angular momentum. How-

ever if a blade is perfectly free to thus readjust itself in the plane of rotation it will readily become displaced from its proper angular relation to other blades, thus causing a bad disturbance in the location of the center of gravity of the rotor. To whatever extent a blade is restrained from thus readjusting itself while the blade is undergoing cyclic changes in its moment of inertia, changes in angular momentum will be introduced thereby introducing both vibration and increase in blade root stresses.

My copending applications Serial No. 645,309, filed February 4, 1946, and Serial No. 665,653, filed April 29, 1946, disclose means for automatically compensating for flapping displacements of a blade so as to stabilize the resultant center of gravity. However, in order to avoid changes in angular momentum in spite of the presence of some degree of restraint of the blade in the lead-lag direction it would be necessary to stabilize the resultant moment of inertia. If this stabilization of the resultant moment of inertia be accomplished by stabilizing the moment of inertia of each blade it will further avoid the increase in blade stresses which would otherwise be introduced by restraining the blade in the lead-lag direction. Stabilizing the center of gravity of the rotor or of the individual blades in the manner disclosed in the above mentioned co-pending applications does not, in general, effect stabilization of the moment of inertia, and it is desirable that both should be stabilized, for blade displacements will, in general, produce either radial displacements of the center of gravity or changes in angular momentum, or both, unless both the center of gravity and moment of inertia of each blade are stabilized. Furthermore if the moment of inertia of each blade be stabilized, the drag hinge may be eliminated and the blade completely restrained in the lead-lag direction without any increase in blade stress under normal flight conditions, and in fact with some decrease from the stresses inherent in the usual arrangement wherein each blade is partially restrained in its movement about the drag hinge.

It is an object of the invention to provide improved means for eliminating vibration in sustaining rotors, and particularly in rotors of articulated construction.

It is an object to render means for automatically stabilizing rotors and/or the blades thereof responsive to blade flexure so as to correct for disturbances in moment of inertia and/or center of gravity produced by such flexure.

It is an object to minimize the forces required to operate such an automatic stabilizing means, and it is a further object to minimize the weight of such means.

More broadly it is the object of the present invention to provide an improved sustaining rotor for rotating wing aircraft.

It is also an object of the invention to provide a rotor which will be particularly easy and inexpensive to manufacture and maintain.

More specifically, it is an object of the invention to remove by particularly improved means the necessity for aerodynamic similarity between the various blades of a rotor, which necessity has been paramount and costly in articulated blade rotors.

The novel features of the invention are set forth with particularity in the appended claims. The invention itself, however, together with additional objects and advantages thereof will be

best understood from the following description of a specific example of an embodiment thereof.

My copending applications hereinabove referred to disclose the use of movable compensating weights located in the blades or on the hub of a sustaining rotor together with means for automatically positioning such weights to stabilize the center of gravity of the rotor and/or the individual blades. It would be possible to alter the form of the positioning means therein disclosed so as to effect stabilization of the moment of inertia of the rotor and/or the blades about the rotor axis, if that were desired, but the specific requirements for positioning such weights to stabilize moment of inertia are, in general, so much at variance with those for positioning them to stabilize center of gravity, that it would be impossible to position weights located as therein disclosed in a manner that would stabilize both the moment of inertia and the center of gravity.

I have discovered, however, that it is possible to arrange a compensating weight in such a manner that it will satisfactorily stabilize both the moment of inertia and the center of gravity of a blade with respect to the axis of rotation of the rotor, and that such dual compensation is dependent upon locating the compensating weight near the center of gravity of the blade and so arranging the displacing means that, as set forth in my copending application Serial No. 645,309, the displacement of the weight with change of flapping angle should be approximately proportional to the value of the expression

$$\left(g \frac{B}{W} + a \right) \text{exsec } A \quad (1)$$

wherein:

g =distance from flapping hinge to center of gravity of blade, measured along blade
 B =mass of uncompensated blade
 W =mass of compensating weight
 a =the distance from the flapping hinge to the center of gravity of the compensating weight with the blade horizontal, that is perpendicular to the rotor axis, and
 A =the effective flapping angle of the blade measured up from the horizontal.

In view of the fact that a compensating weight which is so located becomes subject to relatively large centrifugal forces under flight conditions, I prefer to provide means which will substantially counterbalance these centrifugal forces, thereby minimizing the operating forces which must be exerted by the weight positioning system. Also preferably this counterbalancing means is arranged to automatically readjust its counterbalancing force substantially in proportion to the changes in centrifugal force introduced by radial repositioning of the compensating weight.

The following is a description of my preferred embodiment of the invention as shown in the accompanying drawings, in which:

Figure 1 is a vertical section of the rotor hub and one blade, including the automatic stabilizing mechanism, the section being substantially on line 1-1 of Figure 2, and Figure 2 is an enlarged sectional view of the automatic stabilizing mechanism taken substantially on line 2-2 of Figure 1.

Rotor construction and drive

The invention as illustrated in Figures 1 and 2 can be applied to a rotor of any number of

blades. As shown in Figure 1, each blade 10 comprises a skin or covering 11 integrally mounted on ribs 12, which in turn are integrally attached to the tubular blade spar 13, which spar terminates inwardly in a bearing retainer 14 containing a ball thrust bearing 15 co-axial with the spar. This bearing serves to attach the blade to the connecting link 16 in a manner permitting of the blade being rotated about the spar axis relative to link 16, to effect changes in the pitch setting of the blade. Connecting link 16 is in turn attached by means of flapping hinge 17 to lugs 18 integral with hub member 19. Hub member 19 is in turn pivotally mounted by means of roller bearings 20 and 21, for rotation about cylindrical member 22 fixed in the framework of the craft, and about the co-axial cylindrical member 23 which is attached to member 22 by means of a plurality of bolts 24. Attached to the bottom of hub member 19 by means of a plurality of bolts 30 is a ring 31 having downwardly extending lugs 32 for receiving the roller bearing 20. The spherical roller thrust bearing 33 is interposed between ring 31 and cylindrical member 23, thus serving to transmit to the framework of the craft, the upward thrust of hub member 19, which is primarily the force which sustains the craft in flight. Attached to the top of hub member 19 by means of a plurality of bolts 34 is a plate 35. Interposed between this plate and a flange 36 of cylindrical frame member 23 is ball thrust bearing 37, which serves to sustain the rotor when it is not exerting an upward lift on the craft.

The drive for the rotor comes from the engine (not shown) through transmission shaft 40, which shaft is guided in the upper surface 41 of cylindrical frame member 22. Integral with the upper end of shaft 40 is gear 42 which meshes with idler 43, which idler is rotatably mounted on stud 44 which is integrally mounted in member 22. Idler 43 in turn meshes with teeth 45 cut into the inner face of hub member 19. Hub member 19 is thus rotated upon the fixed cylindrical member 22, 23.

Mechanism responsive to blade flexure

Because of the fact that rotor blades are ordinarily constructed of relatively slight vertical dimension and sustain relatively great aerodynamic loads of uneven and cyclically changing distribution along the length of the blade, such blades are ordinarily subjected to considerable flexing in flight, particularly in a vertical direction. If a blade which is attached to the rotor hub by a flapping hinge is appreciably flexed, the effective flapping position of the blade, and therefore its tracking of the other blades, is dependent upon the direction and amount of the flexing of the blade as well as upon the vertical angular displacement of the root section of the blade about the flapping hinge. In order to take both of these factors into account I provide mechanism which is quantitatively responsive to blade flexure as well as to displacement of the blade about the flapping hinge. This mechanism consists essentially of an element displaceable relative to the hub for measuring blade displacement and a flexible member connecting the element to the outer part of the blade, the flexible member being guided relative to the blade and attached to the element at a point sufficiently remote from the flapping hinge center to render the arrangement responsive to both angular displacement and flexure of the blade. In the particular

form illustrated this mechanism includes a lever 57 (Fig. 1) which constitutes the element above referred to and which is angularly positioned about flapping hinge 17 in response to both vertical flexing of the blade and angular displacement of the blade on flapping hinge 17. This angular positioning of lever 57 is effected by the following mechanism:

Lugs 50 are integrally attached to tubular blade spar 13. Flexible cables or rods 51 are attached to these lugs by means of pins 52 and are led through guides 53, each of which guides may consist of a pair of rollers mounted on a lug integral with spar 13. Guides 53 are so located as to guide one of the cables 51 along a path located above the neutral axis of the blade, and the other along a path located below the neutral axis, and hence are located in portions of the blade which are compressed or extended by vertical flexing of the blade. Near the root of the blade each cable 51 is attached to a connecting link 54 by means of a connecting pin 55. Connecting links 54 are pivotally attached by means of pins 56 to lever 57. Pins 56 are placed considerably further apart than are the pins 52 at the outer ends of cables 51, so that the angular displacement of lever 57 will be correspondingly less than that of lugs 50. The reason for this is so that lever 57 will be angularly displaced in proportion to the average effective angular displacement of the blade relative to the hub due to blade flexing, as measured at the flapping hinge. This angular displacement is substantially that of a line connecting the flapping hinge to a point on the blade somewhere in the vicinity of the average effective center of lift of the blade, and is in any case very considerably less in amount than the angle through which the outer tip portion of the blade has been flexed. Therefore, if lugs 50 are located rather close to the blade tip, pins 56 should be about three times as far apart as pins 52 so that lever 57 will be rocked through about one-third the angle through which lugs 50 are deflected, while if lugs 50 are located further in on the blade the ratio of the distance between pins 50 to that between pins 52 should be correspondingly decreased, so that in any case, whether the spacing is determined by theory or by test, the flexing of the blade in flight shall displace lever 57 through an angle equal to that through which the unflexed blade would have to be rocked around flapping hinge 17 in order to produce substantially the same amount of change in the radius of gyration of the blade or in the location of its center of gravity.

These same connections to lever 57 will also cause that lever to rock about flapping hinge 17 in unison with the blade, for any given condition of blade flexure. Hence lever 57 is angularly positioned about hinge 17 in accordance with the average effective blade position taking into account both blade flexure and rocking of the blade upon the flapping hinge.

In case of a blade construction in which there is no flapping hinge the flexure of the blade will nevertheless ordinarily be sufficient to produce a vertical flapping movement of the blade, and the average axis about which such movement takes place constitutes an effective flapping hinge. The flexure responsive mechanism, therefore, makes it possible to apply the principles of the invention to non-articulated rotors as well as making it possible to apply them more satisfactorily to articulated rotors than would otherwise be possible.

Stabilizing mechanism

The mechanism for stabilizing the location of the center of gravity of the rotor and of each blade thereof, and for stabilizing the value of the radius of gyration of each blade comprises a compensating weight 85 slidably mounted within the tubular spar 13 of each blade, and means for automatically positioning the weight in response to blade flapping and flexure substantially in accordance with the criteria hereinbefore set forth and especially in accordance with expression (1) set forth above.

As previously described lever 57 is rotatably positioned on flapping hinge pin 17 directly in accordance with the rocking of the blade on the flapping hinge plus the amount of flexing of the blade reduced to an equivalent amount of change in blade flapping angle. Each lever 57 therefore occupies at each instant an angular position corresponding to the equivalent effective flapping angular position of the blade at that instant and it is therefore used as a source of control for positioning the compensating weight. For this purpose a slot 65 is cut into the lower part of lever 57 of the proper shape to produce movement in accordance with expression (1) hereinabove. This slot 65 is arranged to embrace a roller 66 which is rotatably mounted on a stud 68 integrally mounted in segment 67 which is rockably mounted on pin 69 integrally supported in lugs 70 integral with hub member 19. Cut into the outer face of segment 67 are gear teeth 71 which mesh with spur gear 72 which is rotatably mounted on flapping hinge pin 17. Integrally attached to spur gear 72 is planetary carrier 73 at the extremities of which are mounted studs 75 carrying planetary pinions 74. These planetary pinions mesh with internal gear 76 which is mounted on studs 56 so as to remain in fixed relation to lever 57. The planetary pinions also mesh with sun gear 78 which is integrally attached to drum 77 and both the drum and sun gear are rotatably mounted on flapping hinge pin 17.

As previously mentioned, the compensating weight 85 is slidably mounted in the interior of tubular blade spar 13. Attached to the inboard end of the weight 85 is tension spring 86, the inboard end of which is attached to the tubular blade spar. This spring is provided for the purpose of counterbalancing as nearly as possible the centrifugal force of the compensating weight. For a given angular velocity the centrifugal force of a weight is directly proportional to the distance from the weight to the center of rotation. Therefore, for a given angular velocity, the change in centrifugal force of a weight, due to a radial movement of the weight, is proportional to the distance that the weight has been shifted radially. Spring 86 has a spring force gradient such that the change in force of the spring for a radial movement of the weight is equal, at a selected angular velocity corresponding substantially to the normal rotor speed, to the change in centrifugal force of the weight for the same radial movement of the weight. With such an arrangement the weight positioning means need only exert a force great enough to overcome frictions plus the amount that centrifugal force may change due to the rotor speed departing from that at which the spring force equals centrifugal force. With compensating weight 85 located at a great radial distance from the rotor axis as required to stabilize both moment of inertia, and

center of gravity, the adjustment of the weight would set up prohibitively great moments between the hub and the blade were it not for the effect of spring 86.

Attached to each end of movable weight 85 is positioning cable 87, the purpose of which is to position the movable weight. Cable 87 passes from the inward end of movable weight 85 through the interior of tension spring 86, thence inwardly through tubular blade spar 13 and through a central hole in connecting link 16. It then passes over pulley 88, which is attached to connecting link 16, and around cable drum 77 to which it is firmly attached and from which it derives its motion. From the outward end of movable weight 85, cable 87 extends outwardly through tubular blade spar 13. It then passes over pulley 89, which is attached to tubular blade spar 13, at which point it passes through the wall of tubular blade spar 13 and extends inwardly optionally being guided by pulleys coaxial with the previously mentioned pulleys 53. Near the root of the blade, cable 87 is guided into the interior of tubular blade spar 13 by means of pulleys 90 which are attached to the tubular blade spar. The cable then passes inwardly through the previously mentioned hole in connecting link 16, over pulley 91, which is attached to connecting link 16, and thence around cable drum 77 to which it is attached.

The operation of this mechanism for automatically positioning the compensating weight 85 may be summarized as follows: Lever 57 is rotatably positioned on hinge pin 17 in accordance with the current effective flapping position of the blade. Cam slot 65 in this lever 57 embraces roller 66 and thereby angularly positions segment 67 on its support pin 69. This motion is transmitted through the previously described planetary gear system and multiplied by it to rotate drum 77 at a faster rate. This rotation of the drum causes displacement of compensating weight 85 along the blade by means of positioning cable 87, so as to position the weight in accordance with expression (1) hereinabove, thus serving to simultaneously and continuously stabilize the center of gravity and radius of gyration of each blade.

By thus stabilizing the effective center of gravity and moment of inertia of each blade it is no longer necessary to endeavor to secure a high degree of aerodynamic similarity or mechanical balance between the blades, for failure of a blade to properly track or otherwise act like the other blades will not disturb rotor operation or cause vibration. Also with the moment of inertia of each blade about the rotor axis maintained constant, the drag hinge may be entirely eliminated, as shown in the accompanying drawings, without causing vibratory cyclic disturbances and without setting up any blade root stresses due to cyclic variations in blade movement, for with constant radius of gyration each blade will tend to maintain constant angular velocity regardless of its cyclic changes of path.

I claim:

1. In an aircraft having a sustaining rotor comprising a hub and a flexible blade attached thereto; means selectively positioned in response to the effective angular position of the blade relative to the hub produced by vertical flexure of the blade, comprising an element supported by the hub and displaceable relative thereto, a flexible member connected at one end to the element for displacing same and connected at the other end

to the blade in the outer portion thereof, and means for guiding said member relative to said blade at a plurality of points along the length of the member, each of said points being vertically removed from the neutral axis of the blade.

2. In an aircraft having a sustaining rotor comprising a hub, a flexible blade, and a hinge connecting the blade to the hub; means selectively positioned in response to the effective 10 angular position of the blade relative to the hub, including both the changes due to vertical flexing of the blade and those due to rocking of the blade on its hinge, comprising an element supported by the hub and displaceable relative thereto, a flexible member connected at one end to said element at a point remote from said hinge and connected at the other end to the blade in the outer portion thereof, and means for guiding said member relative to said blade at a plurality 15 of points along the length of the member, each of said points being vertically removed from the neutral axis of the blade.

3. In an aircraft having a sustaining rotor comprising a hub and a blade mounted for flapping movement relative to the hub; the combination with a mass movable longitudinally of the blade, of means for moving the mass longitudinally of the blade in response to flapping movement of the blade relative to the hub, means for minimizing the force necessary to move said mass along said blade under normal rotor operating conditions, said means comprising a spring biased between the blade and the mass to exert an inward force on the mass substantially equal to the centrifugal force exerted on the mass by the rotation of the rotor at a normal operating speed of rotation, said spring being constructed with a spring force gradient substantially equal to the change in the centrifugal force on said mass per unit change in the position of said mass relative to said blade with said rotor rotating at said normal operating speed of rotation.

4. In an aircraft having a sustaining rotor comprising a hub and a flexible blade attached thereto; the combination of an element supported by the hub and displaceable relative there-

5 to, a flexible member connected at one end to the element for displacing same in response to blade flexure and connected at the other end to the blade in the outer portion thereof, means for guiding said member relative to said blade at a plurality of points along the length of the member, a weight displaceable relative to the blade, and means connecting the element to the weight to displace the weight relative to the blade in amounts quantitatively responsive to the amount of flexure of the blade.

5. In an aircraft having a sustaining rotor comprising a hub, a flexible blade, and a hinge connecting the blade to the hub; the combination of an element supported by the hub and displaceable relative thereto, a flexible member connected at one end to said element at a point remote from said hinge for displacing said element relative to the hub in response to displacements of the blade relative to the hub, including both the displacements due to flexing of the blade and those due to rocking of the blade on its hinge, said flexible member being connected at its other end to the blade in the outer portion thereof, means for guiding said member relative to said blade at a plurality of points along the length of the member, a weight displaceable relative to the blade, and means connecting the element to the weight to displace the weight relative to the blade in amounts quantitatively responsive to the combined amounts of flexure of the blade and rock of the blade on its hinge relative to the hub.
